CLAIM

The ornamental design for a hose reel, as shown and described.

DESCRIPTION

FIG. 1 is a top front left perspective view of the hose reel of the present invention;

FIG. 2 is a top front right perspective view thereof;

FIG. 3 is a front view thereof;

FIG. 4 is a left side view thereof;

FIG. 5 is a right side view thereof;

FIG. 6 is a top view thereof;

FIG. 7 is a bottom front left perspective view thereof;

FIG. 8 is a bottom front right perspective view thereof;

FIG. 9 is a top front left perspective view of the hose reel in a folded state; and,

FIG. 10 is a bottom front right perspective view of the hose reel in a folded state.

The portions of the hose reel illustrated in broken lines are not claimed.

1 Claim, 10 Drawing Sheets
